Patented Apr. 29, 1969

214,003

AUTOMATIC LIGHTER AND DISPENSER

Edward W. Peterson, 2040 Duffy Lane,
Bannockburn, Ill.

Filed Feb. 19, 1968, Ser. No. 10,625

Term of patent 14 years

Int. Cl. D27—05

U.S. Cl. D85—2

Fig. 1

Fig. 2

Fig. 3

Fig. 4

Fig. 5

I claim:

The ornamental design for an automatic lighter and dispenser, substantially as shown and described.
